(57) **CLAIM**

The ornamental design for a vehicle wheel balancer console bezel, as shown and described.

DESCRIPTION

FIG. 1 is a perspective view of the vehicle wheel balancer console bezel of the present invention in the environment of a vehicle wheel balancer flat-panel display console, shown in phantom, which forms no part of the invention, the console bezel overlaps the lower front edge of the flat-panel display, optionally a plurality of buttons and knobs are disposed on the console bezel, as shown in phantom, and which form no part of the invention;

FIG. 2 is a front view of the embodiment shown in FIG. 1; FIG. 3 is a left side view of the embodiment shown in FIG. 1;

FIG. 4 is a right side view of the embodiment shown in FIG. 1;

FIG. 5 is a bottom plan view of the embodiment shown in FIG. 1;

FIG. 6 is a top plan view of the embodiment shown in FIG. 1; and,

FIG. 7 is a back plan view of the embodiment shown in FIG. 1.
